(57) **CLAIM**

The ornamental design for a twisted carabiner, as shown and described.

DESCRIPTION

FIG. 1 is a right side elevation view of my new design for a twisted carabiner.

FIG. 2 is a bottom plan view of FIG. 1.

FIG. 3 is a top plan elevation view of FIG. 1.

FIG. 4 is a left side elevation view of FIG. 1.

FIG. 5 is a rear side elevation view of FIG. 1.

FIG. 6 is front side elevation view of FIG. 1.

FIG. 7 is a top perspective view of FIG. 1.

FIG. 8 is a left side elevation view of an alternate embodiment of my new design for a twisted carabiner.

FIG. 9 is a bottom plan view of FIG. 8.

FIG. 10 is a top plan view of FIG. 8.

FIG. 11 is right side elevation view of FIG. 8.

FIG. 12 is a rear side elevation view of FIG. 8.

FIG. 13 is a front side elevation view of FIG. 8.

FIG. 14 is a top perspective view of FIG. 8.

FIG. 15 is a right side elevation view of an alternate embodiment of my new design for a twisted carabiner.

FIG. 16 is a bottom plan view of FIG. 15.

FIG. 17 is a top plan view of FIG. 15.

FIG. 18 is a left side elevation view of FIG. 15.

FIG. 19 is a rear side elevation view of FIG. 15.

FIG. 20 is a front side elevation view of FIG. 15.

FIG. 21 is a top perspective view of FIG. 15.

FIG. 22 is a left side elevation view of an alternate embodiment of my new design for a twisted carabiner.

FIG. 23 is a bottom plan view of FIG. 22.

FIG. 24 is a top plan view of FIG. 22.

FIG. 25 is a right side elevation view of FIG. 22.

FIG. 26 is rear side elevation view of FIG. 22.

FIG. 27 is a front side elevation view of FIG. 22; and,

FIG. 28 is a top perspective view of FIG. 22.
